UNITED STATES PATENT OFFICE

2,054,935

LAST

John B. Hadaway, Swampscott, Mass., assignor
to United Shoe Machinery Corporation, Paterson, N. J., a corporation of New Jersey

Application March 6, 1935, Serial No. 9,631

5 Claims. (Cl. 12—135)

The present invention relates to lasts, and particularly to separable lasts, the heel parts of which can be removed from shoes made on them without disturbance of their foreparts. It is a principal object of the invention to provide for the use of separable last heel parts made of cast or molded material having superior advantages as regards cheapness and strength, as compared with wood.

I have accordingly provided a strong, light, metallic heel part frame adapted for the casting or molding of a body thereon having the desired heel part contour, comprising a heel plate, a bonding plate for carrying bonding means between the heel part and the forepart, and a thimble. Preferably the heel plate and the bonding plate or joint face member are formed of one piece of steel and the thimble is integrally mounted thereon.

The invention also provides a novel, strong, simple and easily operated bonding mechanism readily permitting the detachment of the heel part from the forepart, without disturbance of the latter when in a shoe. This bonding mechanism comprises a plurality of headed pins on the forepart cooperating with slots in the heel part bonding plate, and a simply operable locking member for properly holding the headed pins in the slots. This locking member is automatically operable in fastening the last parts together, and is operable by the operator only when they are to be separated.

These and other features of the invention comprising certain combinations and arrangements of parts will be apparent from the following description of a preferred embodiment of the invention shown in the drawing, in which

Fig. 1 is a partly sectional side elevation of the last;

Fig. 2 shows the forepart bonding mechanism; Fig. 3 shows the heel part frame; and

Fig. 4 illustrates the unlocking of the last preparatory to the separation of its parts.

The forepart 10 of the illustrated last has a block 12 let into its joint surface 14 and fastened in place by pins 16. The joint surface 14 is plane and extends downward and backward. The block 12 is cast around two pins 18 each having a projecting head or button 20. The embedded shanks are smaller in diameter than

the integral knurled collars 22 and are thus held firmly in the cast block. The knurling of the collars also tends to prevent any looseness. Other constructions for fastening the pins in the block are feasible, but the one illustrated is satisfactory.

The block 12 also carries a spring-pressed plunger 24 projecting beyond the joint face 14 and having shoulders preventing its ejection from the front of the block.

The heel part frame comprises a heel plate 26 formed integrally with the bonding plate 28 as by a suitable stamping operation. This member is preferably formed of steel. The bonding plate 28 has two keyhole slots 30 stamped in it and is also provided with lugs 32, 34 stamped out perpendicular to its plane. These lugs engage and hold the heel part body 36, which is cast or molded on to the heel part frame. The heel plate 26 also carries a flanged collar 38 rigidly fastened to it, as by spot welding, and the thimble 40 has a tight driving fit in this collar. The bottom piece 42 and the space plate 44 are driven into the bottom of the thimble and the latter member and the heel plate have registering holes 25 at 46 for a tack plug. The thimble 40 is ovoid in cross-section, as explained in United States Letters Patent No. 1,436,065, granted November 21, 1922, on the application of L. E. Topham.

The last is assembled by putting the heel part 30 and forepart together with the heads 20 in the larger, lower ends of the slots 30, and pressing the last parts together. At this time the plunger 24 rests against the tongue 48 between the slots and is forced back into the forepart against the pressure of its spring. The heel part is then slid downward over the face 14 until the shanks 18 of the buttons 20 slide into the upper, narrow ends of the slots 30, thus locking the heel part and forepart together. At this time also the 40 locking plunger 24 slips out into the lower end of the upper keyhole slot 30, thus preventing reverse movement of the heel part. This plunger 24 is tapered so as to bind against the sides of the slot 30 in order to take up any variation in 45 the width of the slot. The last parts are thus firmly locked together.

To take the last apart it is put on a jack having a jack pin 50 (Fig. 4) and a sliding plunger 52 is operated by a lever 54, crank arm 56, link 50

58, and lever 60, to push the plunger 24 back into the forepart below the edge of the plate 28. A second lever 62 may then be used to operate a plunger 64 to push the forepart in 5 the direction toward its tread face to release the buttons 20 from the narrow ends of the slots 30, permitting the forepart with a shoe on it to be taken away from the heel part, the angular position of the plane 14 permitting the 10 last to shorten as the forepart moves. The jack illustrated in Fig. 4 is not my invention and is not claimed herein.

Having described my invention, what I claim as new and desire to secure by Letters Patent 15 of the United States is:

1. A separable last having an upwardly and forwardly extending plane cut between its heel part and forepart, each said part having an integral metallic plate in its secant face, one of 20 said plates having a plurality of keyhole slots located one above the other, and the other said plate having a plurality of correspondingly located pins projecting from its secant face, and a locking member slidably located in one of said 25 last parts and arranged to enter a hole in the metallic plate on the other of said last parts when the last is assembled with the headed pins in the smaller ends of the keyhole slots, to prevent movement of said headed pins in the 30 keyhole slots.

2. A separable last having a downwardly and rearwardly extending plane cut between its heel part and forepart, a metallic block mounted flush with the secant face of the forepart having 35 a plurality of headed pins extending from

it, one above the other, and a resilient tapered locking plunger projecting therefrom, a plurally keyhole slotted plate forming a part of the secant face of the heel part, the keyhole slots having their narrow portions at their 5 upper ends, and so arranged that when the headed pins are in the lower wider ends of the slots, the resilient plunger will abut against a portion of the heel part plate, and so that when the headed pins are in the upper narrower 10 ends of the slots the plunger will wedge into the wider end of one of the slots to prevent relative movement between the pins and the heel part plate.

3. A last heel part having a metallic frame 15 comprising a heel plate and a forepart bonding plate angularly formed of a single piece of metal, a flanged collar integrally fastened to the heel plate, a thimble having a close driving fit in said collar, and a body molded on said 20 frame.

4. A last heel part comprising a metallic frame having a heel plate, a thimble and a forepart bonding plate, all integrally fastened together, and a body portion molded on said 25 frame.

5. A last heel part frame formed of an integral obtuse-angled heel plate and forepart bonding member, the bonding member being provided with a plurality of keyhole slots one 30 above the other and with a number of rearwardly projecting lugs, and a thimble rigidly attached to the heel plate.

CERTIFICATE OF CORRECTION.

September 22, 1936.

Patent No. 2,054,935.

JOHN B. HADAWAY.

It is hereby certified that error appears in the printed specification of the above numbered patent requiring correction as follows: Page 2, first column, line 23, claim 1, before the word "pins" insert headed; and that the said Letters Patent should be read with this correction therein that the same may conform to the record of the case in the Patent Office.

Signed and sealed this 5th day of January, A. D. 1937.

Acting Commissioner of Patents.
